United States Patent Office.

AMOS STOCKER, OF WATERTOWN, NEW YORK.

Letters Patent No. 70,915, dated November 12, 1867.

IMPROVED VENTILATING DEVICE FOR BOOTS AND SHOES.

The Schedule referred to in these Letters Patent and making part of the same.

TO ALL WHOM IT MAY CONCERN:

Be it known that I, AMOS STOCKER, of Watertown, in the county of Jefferson, in the State of New York, have invented a new and improved Manner of Ventilating Boots and Shoes; and I do hereby declare that the following is a full and exact description thereof, reference being had to the accompanying drawings, and to the letters of reference marked thereon.

The nature of my invention consists in providing the toe of a boot or shoe with a valve, so that in walking or pressing the foot down, the air will be forced outside through the valve, which prevents it from returning to inside of boot again. I also provide an extra insole from toe back to the shank, where it is secured, (after a number of springs have been inserted between it and the regular insole towards the toe,) the use of which is to help throw up the foot against the upper leather, (where a good deal of ventilation is necessary,) forming a larger vacuum and a more perfect ventilation.

To enable others skilled in the art to make and use my invention, I will proceed to describe its construction and operation.

I make the boot or shoe as they are generally made. I then take a piece of brass or other material, (such as gutta percha or rubber,) and form it about the shape of a rivet, the head being about a half inch in diameter across the head, and the stem I make about one-fourth of an inch in diameter and nearly one-fourth inch long. I then cut a fine thread (such as are cut on screws) on the stem, and drill a hole through the centre, from small end up through centre of head, as seen in Figures 1 and 2. I then form a cap or cover about one-fourth inch high, (with a screw-thread cut on the inside about half way up,) the size suitable to screw on over figs. 1 and 2, having air-holes through inside at covered end, with a flange formed as close to covered end as possible, about one-eighth of one inch wide, and just below the air-escape hole or holes, (see a perspective view of bottom, Figure 3, and side and upright views, Figure 4.) I then take the hollow rivet, before described, and screw it into cap, fig. 4, as seen in Figure 5. The flanges are used for the purpose of holding the upper leather securely between them, as in figs. 1 and 4 and are screwed together in the toe of boot or shoe, (see Figure 6.) I then form a portion of an insole, from leather or other material, from the toe to the shank. The end toward the heel is shaved to a thin edge when made of thick leather, so as not to hurt the foot. (I think some of using some kind of spring metal instead of the leather. In that case I shall not use the spiral springs.) I then secure a number of small spiral springs, so made as to shut down, so that there will only be one thickness of wire between the two soles. The springs are so placed between the two soles, near enough together so as not to form bunches under the foot. I then fasten the thin end of sole to shank in any of the known ways, (see fig. 6, letter A.) The springs I use for the purpose of forcing up the ball of the foot, thereby causing a more perfect vacuum or a larger one. This extra insole is not indispensable, because some will not require any more ventilation than the instrument with its valve, seen in fig. 5, and on toe of boot, fig. 6. I also take a thin piece of rubber, quite smooth, and of a suitable size to act as a valve, on small end of hollow rivet, (see fig. 2, letter B,) after which it is screwed up into fig. 4, (see figs. 5 and 6.)

I did obtain Letters Patent in September, 1864, No. 44,467; but I changed the air in a boot or shoe by means of a bellows placed under the foot; but this invention is used so as to force the air out from the foot through one valve.

What I claim as my invention, and desire to secure by Letters Patent, is—

1. The instrument seen in figs. 5 and 6, letter C, in combination with a boot or shoe.
2. I also claim the extra insole, with its spring or springs, in combination with the valve, as seen in fig. 6, letter C, substantially as described and for the purposes set forth in the specification.

AMOS STOCKER.
